FIG. 1

FIG. 2

**VOLTAGE REGULATION CIRCUIT
SUPPLYING REFERENCE VOLTAGE TO
DISPLAY DEVICE**

TECHNICAL FIELD

The present disclosure relates to a field of display technology, and particularly to a voltage regulator circuit and a display device.

BACKGROUND

The thin film transistor liquid crystal display (TFT-LCD) is one of the main types of flat panel display. The basic driving principle of TFT-LCD is as follows: R/G/B compressed signal and power control are signal transmitted through a wire from the system board to the printed circuit board (PCB), and are processed by the timing controller (TCON) and integrated circuit (IC) on the PCB, then are transmitted to a display area by the source chip-on-film (S-COF) and the gate chip-on-film (G-COF), thereby the display receiving the required power and signal.

In order to ensure that the voltage outputted from the S-COF conforms to the viewing habit of the human eye, it is necessary to input a reference voltage to the S-COF as a reference value of the output voltage. In the conventional configuration, an external power chip supplies a constant supply voltage to a reference voltage chip, so as to generate the required reference voltage. Due to the design of the reference voltage chip, the outputted reference voltage can only be less than the supply voltage. Since the supply voltage from a conventional external power chip can be unstable, when the supply voltage is too high, the temperature of the S-COF is too high. When the supply voltage is too low, the reference voltage required cannot be generated. And when the supply voltage is determined, if the supply voltage value needs to be changed, the hardware circuit needs to be changed, which is costly and inefficient.

SUMMARY

According to various embodiments of the present disclosure, a voltage regulator circuit and a display device are provided.

A voltage regulator circuit includes:
a power chip;
a controlling chip, configured to transmit a control signal; and

a regulating chip, connected to the power chip and the controlling chip, and configured to regulate an outputted voltage from the power chip to a preset voltage according to the control signal, and transmit the preset voltage to the controlling chip.

The controlling chip is further configured to convert the preset voltage to a reference voltage.

In one of the embodiments, the regulating chip includes:
a first gate circuit connected to the controlling chip, and configured to receive the controlling signal;
a second gate circuit connected to the controlling chip, and configured to receive the controlling signal; and
a bias circuit, the first gate circuit is connected in parallel with the second gate circuit and the connected first gate circuit and second gate circuit are in series with the bias circuit, and the first gate circuit, second gate circuit, and the bias circuit are located between a voltage output terminal of the power chip and ground.

The control signal includes: a first control signal turning on the first gate circuit while turning off the second gate circuit, and a second control signal turning off the first gate circuit while turning on the second gate circuit.

5 In one of the embodiments, the first control signal is at a high level, and the second control signal is at a low level.

In one of the embodiments, the preset voltage includes a first preset voltage and a second preset voltage;

in response to detecting that the controlling chip transmits

10 the first control signal to the first gate circuit and the second gate circuit, the first gate circuit is tuned on, the outputted voltage from the power chip is regulated to the first preset voltage and is transmitted to the controlling chip;

in response to detecting that the controlling chip transmits

15 the second control signal to the first gate circuit and the second gate circuit, the second gate circuit is tuned on, the outputted voltage from the power chip is regulated to the second preset voltage and is transmitted to the controlling chip.

20 In one of the embodiments, the first preset voltage is 15V, and the second preset voltage is 18V.

In one of the embodiments, the voltage regulator circuit further includes a feedback circuit. The feedback circuit is connected to the bias circuit and the power circuit, respectively, and the feedback circuit is configured to detect a bias voltage of the bias circuit and feedback the detected bias voltage to the power chip.

In response to detecting that the bias voltage is equal to a preset bias voltage, the outputted voltage from the power chip remains constant, in response to detecting that the bias voltage is less than the preset bias voltage, the outputted voltage is increased, and in response to detecting that the bias voltage is greater than the preset bias voltage, the outputted voltage is reduced.

35 In one of the embodiments, the preset bias voltage is 1.5V.

In one of the embodiments, the first gate circuit includes:
a first resistor, and

a first electronic switch, a first terminal of the first electronic switch is connected to the voltage output terminal

40 of the power chip via the first resistor, a second terminal of the first electronic switch is connected to the controlling chip, and a third terminal of the first electronic switch is connected to the bias circuit.

In one of the embodiments, the first electronic switch is a

45 NMOS transistor, the first terminal, the second terminal and the third terminal of the first electronic switch correspond to a drain, a gate, and a source of the NMOS transistor, respectively.

In one of the embodiments, the first electronic switch is a
50 NPN transistor, the first terminal, the second terminal and the third terminal of the first electronic switch correspond to a collector, a base, and an emitter of the NPN transistor, respectively.

In one of the embodiments, the second gate circuit includes:
55 a second resistor, and

a second electronic switch, a first terminal of the second electronic switch is connected to the voltage output terminal of the power chip via the second resistor, a second terminal of the second electronic switch is connected to the controlling chip, and a third terminal of the second electronic switch is connected to the bias circuit.

In one of the embodiments, the second electronic switch is a PMOS transistor, the first terminal, the second terminal and the third terminal of the second electronic switch correspond to a drain, a gate, and a source of the PMOS transistor, respectively.

In one of the embodiments, the second electronic switch is a PNP transistor, the first terminal, the second terminal and the third terminal of the second electronic switch correspond to a collector, a base, and an emitter of the PNP transistor, respectively.

In one of the embodiments, the bias circuit includes a third resistor, a first terminal of the third resistor is connected to the third terminal of the first electronic switch, the third terminal of the second electronic switch, and the feedback circuit, respectively, and a second terminal of the third resistor is grounded.

In one of the embodiments, the reference voltage includes a first reference voltage converted from the first preset voltage via the controlling chip, and a second reference voltage converted from the second preset voltage via the controlling chip.

In one of the embodiments, the first reference voltage is less than the first preset voltage, and the second reference voltage is less than the second preset voltage.

A voltage regulator circuit includes:

- a power chip;
- a controlling chip, configured to transmit a control signal; and
- a regulating chip, including:
  - a first gate circuit connected to the controlling chip, and configured to receive the controlling signal;
  - a second gate circuit connected to the controlling chip, and configured to receive the controlling signal; and
  - a bias circuit, wherein the first gate circuit is connected in parallel with the second gate circuit and the connected first gate circuit and second gate circuit are in series with the bias circuit, and the first gate circuit, second gate circuit, and the bias circuit are located between a voltage output terminal of the power chip and ground.

The control signal includes: a first control signal turning on the first gate circuit while turning off the second gate circuit, and a second control signal turning off the first gate circuit while turning on the second gate circuit.

The first gate circuit converts an outputted voltage from the power chip to a first preset voltage according to the first control signal.

The second gate circuit converts the outputted voltage from the power chip to a second preset voltage according to the second control signal.

The controlling chip is further configured to convert the first preset voltage to a first reference voltage, and convert the second preset voltage to a second reference voltage.

A display device includes a source chip-on-film and an aforementioned voltage regulator circuit. The voltage regulator circuit is configured to input a reference voltage to the source chip-on-film.

The details of one or more embodiments of present disclosure are set forth in the accompanying drawings and the description below. Other features, objects, and advantages of present disclosure will be apparent from the description and drawings, and from the claims.

BRIEF DESCRIPTION OF THE DRAWINGS

To illustrate the technical solutions according to the embodiments of the present disclosure or in the prior art more clearly, the accompanying drawings for describing the embodiments or the prior art are introduced briefly in the following. Apparently, the accompanying drawings in the following description are only some embodiments of the

present disclosure, and persons of ordinary skill in the art can derive other drawings from the accompanying drawings without creative efforts.

FIG. 1 is a circuit diagram of a voltage regulator circuit according to an embodiment; and

FIG. 2 is a schematic diagram of a display device according to an embodiment.

DETAILED DESCRIPTION OF THE EMBODIMENTS

It will be understood that when an element is referred to as being "connected" or "coupled" to another element, it can be directly connected or coupled to the other element or intervening elements may be present. Unless otherwise defined, all terms (including technical and scientific terms) used herein have the same meaning as commonly understood by one of ordinary skill in the art to which this invention belongs. The terms used herein is for the purpose of describing particular embodiments only and is not intended to limit the present disclosure.

Referring to FIG. 1, a voltage regulator circuit includes a power chip 10, a regulating chip 20, and a controlling chip 30. The regulating chip 20 connected to the power chip 10 and the controlling chip 30. The controlling chip 30 is configured to transmit a control signal to the regulating chip 20. The regulating chip 20 is configured to regulate an outputted voltage from the power chip 10 to a preset voltage according to the control signal, and transmit the preset voltage to the controlling chip 30. The controlling chip 30 is further configured to convert the preset voltage to a reference voltage. The controlling chip 30 is also configured to input the reference voltage to the S-COF, and the reference voltage is used as a reference value of an outputted voltage from the S-COF.

In one of the embodiments, the power chip 10 is a DC to DC power management chip. The controlling chip 30 is a microcontroller unit (MCU).

The regulating chip 20 includes a first gate circuit 21, a second gate circuit 22, and a bias circuit 23. The first gate circuit 21 is connected in parallel with the second gate circuit 22 and the connected first gate circuit 21 and second gate circuit 22 are in series with the bias circuit 23. The first gate circuit 21, second gate circuit 22, and the bias circuit 23 are located between a voltage output terminal of the power chip 10 and ground. The first gate circuit 21 and the second gate circuit 22 are both connected to the controlling chip 30, so as to receive the controlling signal.

The control signal comprises: a first control signal that turns on the first gate circuit 21 while turning off the second gate circuit 22, and a second control signal turning off the first gate circuit 21 while turning on the second gate circuit 22.

The preset voltage includes a first preset voltage and a second preset voltage.

When the controlling chip 30 transmits the first controlling signal to the first gate circuit 21 and the second gate circuit 22, the first gate circuit 21 is turned on, the outputted voltage from the power chip 10 is regulated to the first preset voltage and is transmitted to the controlling chip 30. When the controlling chip 30 transmits the second control signal to the first gate circuit 21 and the second gate circuit 21, the second gate circuit 21 is turned on, the outputted voltage from the power chip 10 is regulated to the second preset voltage and is transmitted to the controlling chip 30.

In one of the embodiments, the first control signal is at a high level, and the second control signal is at a low level.

The voltage regulator circuit further includes a feedback circuit **40**, the feedback circuit **40** is connected to the bias circuit **23** and the power circuit **10**, respectively. The feedback circuit **40** is configured to detect a bias voltage of the bias circuit **23** and feedback the detected bias voltage to the power chip **10**. When the bias voltage is equal to a preset bias voltage, the outputted voltage from the power chip **10** remains constant. When the bias voltage is less than the preset bias voltage, the outputted voltage is increased. When the bias voltage is greater than the preset bias voltage, the outputted voltage is reduced. The power chip **10** determines the change of the outputted voltage through the bias voltage fed back by the feedback circuit **40**, and regulates the magnitude of the outputted voltage according to the change of the outputted voltage, such that the outputted voltage remains constant. In one of the embodiment, the preset bias voltage is 1.5V.

The first gate circuit **21** includes a first resistor **R1** and a first electronic switch **Q1**. A first terminal **2011** of the first electronic switch **Q1** is connected to the voltage output terminal **1011** of the power chip **10** via the first resistor **R1**, a second terminal **2012** of the first electronic switch **Q1** is connected to the controlling chip **30**, and a third terminal **2013** of the first electronic switch **Q1** is connected to the bias circuit **23**.

In the illustrated embodiment, the first electronic switch **Q1** is a NMOS transistor or a NPN transistor, the first terminal **2011**, the second terminal **2012** and the third terminal **2013** of the first electronic switch **Q1** correspond to a drain, a gate, and a source of the NMOS transistor, or a collector, a base, and a emitter of the NPN transistor, respectively. In other embodiments, the first electronic switch **Q1** can be any other switch with similar functions.

The second gate circuit **22** includes a second resistor **R2** and a second electronic switch **Q2**. A first terminal **2021** of the second electronic switch **Q2** is connected to the voltage output terminal **1011** of the power chip **10** via the second resistor **R2**, a second terminal **2022** of the second electronic switch **Q2** is connected to the controlling chip **30**, and a third terminal **2023** of the second electronic switch **Q2** is connected to the bias circuit **23**.

In the illustrated embodiment, the second electronic switch **Q2** is a PMOS transistor or a PNP transistor, the first terminal **2021**, the second terminal **2022** and the third terminal **2023** of the second electronic switch **Q2** correspond to a drain, a gate, and a source of the PMOS transistor, or a collector, a base, and a emitter of the PNP transistor, respectively. In other embodiments, the second electronic switch **Q2** can be any other switch with similar functions.

The bias circuit **23** includes a third resistor **R3**, a first terminal **2031** of the third resistor **R3** is connected to the third terminal **2013** of the first electronic switch **Q1**, the third terminal **2023** of the second electronic switch **Q2**, and the feedback circuit **40**, respectively, and a second terminal **2032** of the third resistor **R3** is grounded.

The operation of the voltage regulator circuit will be described below.

The reference voltage includes a first reference voltage converted from the first preset voltage via the controlling chip **30**, and a second reference voltage converted from the second preset voltage via the controlling chip **30**. When the reference voltage that the S-COF needs to input is the first reference voltage, the controlling chip **30** transmits the first control signal to the second terminal of the first electronic switch **Q1** and the second terminal of the second electronic switch **Q2**, the first electronic switch **Q1** is turned on, that is, the first gate circuit **21** is turned on, the second electronic

switch **Q2** is turned off, that is, the second gate circuit **22** is turned off, sum of the first resistor **R1** and the third resistor **R3** is transmitted by the first gate circuit **21** to the control chip **30** as a first preset voltage, then the controlling chip **30** converts the first preset voltage to the first reference voltage. When the reference voltage that the S-COF needs to input is the second reference voltage, the controlling chip **30** transmits the second control signal to the second terminal of the first electronic switch **Q1** and the second terminal of the second electronic switch **Q2**, the first electronic switch **Q1** is turned off, that is, the first gate circuit **21** is turned off, the second electronic switch **Q2** is turned on, that is, the second gate circuit **22** is turned on, sum of the second resistor **R2** and the third resistor **R3** is transmitted by the second gate circuit **22** to the control chip **30** as a second preset voltage, then the controlling chip **30** converts the first preset voltage to the second reference voltage. The first reference voltage is less than the first preset voltage, and the second reference voltage is less than the second preset voltage.

In one of the embodiments, the first preset voltage is 15V, and the second preset voltage is 18V.

Referring to the FIG. 2, the present disclosure also provides a display device. The display device includes a printed circuit board (PCB) **101**, an S-COF **102**, a G-COF **103**, a display panel **104**, and an aforementioned voltage regulator circuit. The voltage regulator circuit is configured to input a reference voltage to the S-COF **102**. The PCB **101** is connected to the display panel **104** through the S-COF **102** and the G-COF **103**. A signal from a system board is transmitted to the PCB **101**, and is processed by a timing controller on the PCB **101**, then is transmitted to the display panel **104** through the S-COF **102** and the G-COF **103**.

For example, the display panel **104** can be a liquid crystal display panel, but is not limited thereto. The display panel **104** can also be an OLED display panel, a W-OLED display panel, a QLED display panel, a plasma display panel, a curved surface display panel, or other type of display panel.

The voltage regulator circuit according to the present disclosure can provide a determined supply voltage to the controlling chip **30** according to the actual reference voltage requirements of the S-COF. Additionally, when the supply voltage to the controlling chip **30** is required to be changed, the hardware circuit is not required to be changed, such that the cost is lower and the efficiency of voltage changing is improved.

As used herein, the terms "unit", "module" and "system" and the like are intended to mean a computer-related entity, which may be hardware, a combination of hardware and software, software, or software in execution. For example, a unit may be, but is not limited to being, a process running on a processor, a processor, an object, an executable, a thread of execution, a program, and/or a computer. By way of illustration, both an application running on a server and the server can be a component. One or more components may reside within a process and/or thread of execution and a component may be localized on one computer and/or distributed between two or more computers.

The technical features of the embodiments described above can be arbitrarily combined. In order to make the description succinct, there is no describing of all possible combinations of the various technical features in the foregoing embodiments. It should be noted that there is no contradiction in the combination of these technical features which should be considered as the scope of the description.

Although the present disclosure is illustrated and described herein with reference to specific embodiments, the present disclosure is not intended to be limited to the details

shown. It is to be noted that, various modifications may be made in the details within the scope and range of equivalents of the claims and without departing from the present disclosure. Therefore, the protection scope of the present disclosure shall be subject to the protection scope of the claims.

What is claimed is:

1. A voltage regulator circuit, comprising:
a power chip;
a controlling chip, configured to transmit a control signal; and
a regulating chip, connected to the power chip and the controlling chip, and configured to regulate an outputted voltage from the power chip to a preset voltage according to the control signal, and transmit the preset voltage to the controlling chip;
wherein the controlling chip is further configured to convert the preset voltage to a reference voltage, wherein the regulating chip comprises:
a first gate circuit connected to the controlling chip, and configured to receive the controlling signal;
a second gate circuit connected to the controlling chip, and configured to receive the controlling signal; and
a bias circuit, wherein the first gate circuit is connected in parallel with the second gate circuit and the connected first gate circuit and second gate circuit are in series with the bias circuit, and the first gate circuit, second gate circuit, and the bias circuit is located between a voltage output terminal of the power chip and ground;
wherein the control signal comprises: a first control signal turning on the first gate circuit while turning off the second gate circuit, and a second control signal turning off the first gate circuit while turning on the second gate circuit.
2. The voltage regulator circuit according to claim 1, wherein the first control signal is at a high level, and the second control signal is at a low level.
3. The voltage regulator circuit according to claim 1, wherein the preset voltage comprises a first preset voltage and a second preset voltage;
in response to detecting that the controlling chip transmits the first control signal to the first gate circuit and the second gate circuit, the first gate circuit is tuned on, the outputted voltage from the power chip is regulated to the first preset voltage and is transmitted to the controlling chip;
in response to detecting that the controlling chip transmits the second control signal to the first gate circuit and the second gate circuit, the second gate circuit is tuned on, the outputted voltage from the power chip is regulated to the second preset voltage and is transmitted to the controlling chip.
4. The voltage regulator circuit according to claim 3, wherein the first preset voltage is 15V, and the second preset voltage is 18V.
5. The voltage regulator circuit according to claim 3, wherein the reference voltage comprises a first reference voltage converted from the first preset voltage via the controlling chip, and a second reference voltage converted from the second preset voltage via the controlling chip.
6. The voltage regulator circuit according to claim 5, wherein the first reference voltage is less than the first preset voltage, and the second reference voltage is less than the second preset voltage.
7. The voltage regulator circuit according to claim 1, further comprising a feedback circuit, wherein the feedback circuit is connected to the bias circuit and the power circuit,

respectively, and the feedback circuit is configured to detect a bias voltage of the bias circuit and feedback the detected bias voltage to the power chip;

in response to detecting that the bias voltage is equal to a preset bias voltage, the outputted voltage from the power chip remains constant, in response to detecting that the bias voltage is less than the preset bias voltage, the outputted voltage is increased, and in response to detecting that the bias voltage is greater than the preset bias voltage, the outputted voltage is reduced.

8. The voltage regulator circuit according to claim 7, wherein the preset bias voltage is 1.5V.

9. The voltage regulator circuit according to claim 1, wherein the first gate circuit comprises:

a first resistor, and
a first electronic switch, wherein a first terminal of the first electronic switch is connected to the voltage output terminal of the power chip via the first resistor, a second terminal of the first electronic switch is connected to the controlling chip, and a third terminal of the first electronic switch is connected to the bias circuit.

10. The voltage regulator circuit according to claim 9, wherein the first electronic switch is a NMOS transistor, the first terminal, the second terminal and the third terminal of the first electronic switch correspond to a drain, a gate, and a source of the NMOS transistor, respectively.

11. The voltage regulator circuit according to claim 9, wherein the first electronic switch is a NPN transistor, the first terminal, the second terminal and the third terminal of the first electronic switch correspond to a collector, a base, and an emitter of the NPN transistor, respectively.

12. The voltage regulator circuit according to claim 9, wherein the second gate circuit comprises:

a second resistor, and
a second electronic switch, wherein a first terminal of the second electronic switch is connected to the voltage output terminal of the power chip via the second resistor, a second terminal of the second electronic switch is connected to the controlling chip, and a third terminal of the second electronic switch is connected to the bias circuit.

13. The voltage regulator circuit according to claim 12, wherein the second electronic switch is a PMOS transistor, the first terminal, the second terminal and the third terminal of the second electronic switch correspond to a drain, a gate, and a source of the PMOS transistor, respectively.

14. The voltage regulator circuit according to claim 12, wherein the second electronic switch is a PNP transistor, the first terminal, the second terminal and the third terminal of the second electronic switch correspond to a collector, a base, and an emitter of the PNP transistor, respectively.

15. The voltage regulator circuit according to claim 12, wherein the bias circuit comprises a third resistor, a first terminal of the third resistor is connected to the third terminal of the first electronic switch, the third terminal of the second electronic switch, and the feedback circuit, respectively, and a second terminal of the third resistor is grounded.

16. A display device, comprising a source chip-on-film, and the voltage regulator circuit according to claim 1, wherein the voltage regulator circuit is configured to input a reference voltage to the source chip-on-film.

17. A voltage regulator circuit, comprising:
a power chip;
a controlling chip, configured to transmit a control signal; and

a regulating chip, comprising:
a first gate circuit connected to the controlling chip, and
configured to receive the controlling signal;
a second gate circuit connected to the controlling chip,
and configured to receive the controlling signal; and 5
a bias circuit, wherein the first gate circuit is connected
in parallel with the second gate circuit and the
connected first gate circuit and second gate circuit
are in series with the bias circuit, and the first gate
circuit, second gate circuit, and the bias circuit are 10
located between a voltage output terminal of the
power chip and ground;
wherein the control signal comprises: a first control signal
turning on the first gate circuit while turning off the
second gate circuit, and a second control signal turning 15
off the first gate circuit while turning on the second gate
circuit;
the first gate circuit converts an outputted voltage from
the power chip to a first preset voltage according to the
first control signal; 20
the second gate circuit converts the outputted voltage
from the power chip to a second preset voltage accord-
ing to the second control signal; and
the controlling chip is further configured to convert the
first preset voltage to a first reference voltage, and 25
convert the second preset voltage to a second reference
voltage.
